SETH WHEELER AND EDGAR JEROME, OF ALBANY, NEW YORK.

Letters Patent No. 66,918, dated July 16, 1867.

IMPROVEMENT IN DRYING BOXES, &c., OF PULP.

The Schedule referred to in these Letters Patent and making part of the same.

TO ALL WHOM IT MAY CONCERN:

Be it known that we, SETH WHEELER and EDGAR JEROME, of Albany, State of New York, have invented a new and useful Mode of Drying Boxes and other Hollow Articles made directly from Paper-Pulp and other analogous substances; and we do hereby declare that the following is a full, clear, and exact description of the same, reference being had to the accompanying drawings, forming part of this specification.

The invention which forms the subject of this patent is a drying-frame, which is rigid vertically, but capable of contracting and expanding horizontally. This frame fits over the form, upon or within which a box, lamp-shade, or any other hollow articles, and particularly such as are mentioned in the Letters Patent granted to Edward H. Knight, April 3, 1866, and to us, February 12, 1867, may be dried after their manufacture from paper-pulp or other analogous material has been effected either by atmospheric or mechanical pressure, on the principles set forth in the above-mentioned patents.

To employ the rigid frame A, in connection with the atmospheric process, it must be constructed with a series of fine holes through it, so that the suction of an air-pump or any other pneumatic machine may draw the pulp upon it, and thus form the desired article in a perfect manner. The frame A, as shown in the drawing, is of cylindrical form, open at both ends, and split from top to bottom at one point, as indicated at a. It is made of finely reticulated metal or of perforated hard rubber, or of any thin, rigid substance which will answer the purpose desired, viz., to sustain the box in its proper form while it is drying. The split in the rigid frame is to permit it to expand before the box is formed, and then to allow it to contract as the box contracts while drying. The expansibility of the frame is a matter of some moment in the removal of the box from it, for, just in proportion as it is capable of expanding, so may it be contracted, and thus be brought to a condition for ready withdrawal from the box. In the use of the rigid frame, in connection with the atmospheric process, the paper-pulp may be formed into a box either upon or within the frame upon the principles of operation set forth in the said patent of Knight, and therefore may be dried upon or within the frame. Hollow articles may be dried upon the rigid frames either prior or subsequent to the removal of the frames from the forms or dies. In any case, the form may be removable from the machine or not as may be most advantageous. Such mode of drying may be pursued with hollow articles made by the atmospheric, mechanical, or other pressure process. In the use of the rigid drying frame, in connection with any other than the atmospheric process of making hollow articles, we prefer to use a perforated frame, although an unperforated one may be used.

The drawings, figs. 1, 2, 3, 4, 5, show a former adapted for use in connection with the frame A, and for making the body of a cylindrical box by the Knight process. This former consists of a hollow cylinder, B, closed at its upper end by a perforated head, b, and at its lower end by a head, b', provided with a suction pipe, C. The lower head forms a shoulder, c, outside of the circumference of the cylinder B, as shown. About midway of the length of the cylinder B a depression or channel, c', is formed all round, and the metal forming the base of this channel is perforated so as to form passages into the cylinder. Extending up from this channel to the terminus of the cylinder are a number of narrow channels, d d, which are cut into the circumference of the cylinder. Around the lower half, and little more, of the cylinder, a sliding-collar, D, is fitted so as to rest on the shoulder c, cover the channel c', and also the lower ends of the channels d d, as shown. Upon the upper end of the cylinder, which is channelled and perforated, as shown at f, a perforated circle-plate, g, of the same diameter as the cylinder, is fitted and held in place by means of a hollow or solid stem, e, which enters the head of the cylinder, as shown. And around the remaining uncovered portion of the cylinder B, which portion is channelled vertically, as described, the rigid drying frame A is placed in the manner represented. The "former," thus constructed, is arranged in a vat of paper-pulp, so as to have the rigid frame completely surrounded, and the lower end of the pipe C is connected to a suction apparatus. All thus arranged, the suction or air-pump is set in motion, and its effect is to create a suction through the perforated plate g, and through the perforated drying-frame, and along the channels, in such a manner as to cause the pulp to deposit evenly and to a proper thickness upon the surface of the plate, and upon the drying-frame in the form of the cylindrical body and the bottom of a box, such as shown in fig. 6. The body of the box thus formed is forced off the "former" with the drying-frame within the body by means of the sliding-collar D. In fig. 3 we have shown the box slipped partly off by this collar, and in fig. 6 we have shown the box, with the drying-frame within it

entirely off the "former" or die, and as it appears when set for drying. In fig. 7 the frame is shown in perspective, disconnected from the box, and in fig. 8 the finished body of the box is shown.

The top of the box is made in substantially the same manner as the body, upon a die or "former" and drying-frame corresponding to the shape and depth of the top. If conical, many-sided, or any other geometrical form, is to be given to the hollow articles, all that is necessary is to employ dies or "formers" and drying-frames, which will give the desired form.

We will state here that where boxes or other hollow articles are produced by the atmospheric process, it is necessary to subject them to a rolling or pressing operation, so as to give them a finished appearance on their inner and outer surfaces; but when made by the pressure process, as patented by us February, 1867, this is not necessary. The pressing or finishing process, however, forms no part of this patent, but is covered by a separate patent of even date with this.

Having thus described our invention, we will state that we do not confine ourselves to the particular means herein described and referred to for making boxes and other hollow articles from paper-pulp and analogous substances, as the invention here patented is a mode of drying the articles after they are made.

What we claim, therefore, as our invention, and desire to secure by Letters Patent, is—

Drying the hollow articles made directly from the paper-pulp or other analogous substance, upon or within a frame, which is rigid vertically but expansible horizontally, such frame being the one upon which the articles are made.

SETH WHEELER,
EDGAR JEROME.
